Primary Examiner — Mary Shannon Malley*Assistant Examiner* — Dustin Andrew Griffith(74) *Attorney, Agent, or Firm* — Gallium Law; Wesley Schwie, Esq.; Isabel Fox(57) **CLAIM**

The ornamental design for a wallet, as shown and described.

DESCRIPTION

FIG. 1 is a front, first side, and bottom perspective view of a wallet embodying the new design;

FIG. 2 is a back, first side, and top perspective view thereof;

FIG. 3 is a front view thereof;

FIG. 4 is a back view thereof;

FIG. 5 is a top view thereof;

FIG. 6 is a bottom view thereof;

FIG. 7 is a first side view thereof; and,

FIG. 8 is a second side view thereof.

The evenly dashed broken lines on claimed surfaces depict stitching and form no part of the claimed design.
